UNITED STATES PATENT OFFICE.

CHARLES E. GILLETT, OF WORCESTER, MASSACHUSETTS, ASSIGNOR TO NORTON COMPANY, OF WORCESTER, MASSACHUSETTS, A CORPORATION OF MASSACHUSETTS.

PROCESS AND APPARATUS FOR CLASSIFYING GRINDING WHEELS.

Application filed March 7, 1919. Serial No. 281,303.

To all whom it may concern:

Be it known that I, CHARLES E. GILLETT, a citizen of the United States of America, residing at Worcester, in the county of 5 Worcester and State of Massachusetts, have invented certain new and useful Improvements in Processes and Apparatus for Classifying Grinding Wheels, of which the following is a full, clear, and exact specification.

My invention relates to the art of classifying grinding wheels and similar articles. The methods heretofore proposed for grading wheels made of abrasive grains bonded by suitable materials, such as vitrified ceramic clays, have involved testing the 15 wheels while stationary and not while acting under true grinding conditions. For example, wheel manufacturers have tried to grade wheels by measuring the depth of 20 penetration of a chisel or flat edged tool like a screw driver which is rotated by power against the wheel or by observing the "feel" of the tool when rotated by 25 hand. It has also been proposed to measure the wear of the tool thus rotated against the stationary wheel. However, in actual 30 operation a grinding wheel rotates at such a high velocity that the projecting grains of abrasive, having considerable momentum, 35 cut their way deeply through the work and produce long thick chips of metal, whereas a slowly moving abrasive body would merely wear down the metal by a frictional 40 scratching action of low efficiency and the abrasive grains would break away from their settings more readily than when rotated rapidly. The result of grinding at 45 this high rate of velocity gives an apparent increase in hardness to the wheel. A microscopic examination of the metal chips removed by grinding iron shows that the abrasive particles act as chisels or cutting tools, if they have sharp edges and have 50 not become glazed. If on the other hand the grains are dull or have become glazed the particles removed from the metal are frequently rounded in shape and show that considerable heat has been generated, even 55 to the extent of forming fused iron globules. When the grains become dull, it is necessary that the wheel be dressed or have its 60 surface renewed by breaking away the grains from the bond and presenting fresh

cutting edges to the work. That wheel 55 which remains unglazed for the longest time is therefore the more desirable of two which otherwise have the same rate of cutting.

In order to obtain a correct classification for a given wheel corresponding with its 60 actual use in the art, it is an object of my invention to classify wheels by means of tests which are conducted under conditions of stress and wheel strain similar to those found in the ordinary operation of the 65 wheel in regular use.

A further object is to provide an apparatus and a process for grinding a test tool by means of the wheel to be classified, recording or measuring certain results of the 70 operation and utilizing the data obtained to identify and classify various essential characteristics which are inherently associated with the grinding ability of the wheel.

Still further objects will be apparent in 75 the following disclosure.

In order that my invention may be fully understood I have illustrated in the drawing a diagrammatic representation of the 80 essential features of an apparatus adapted to carry out this method of classification of wheels:

Fig. 1 is an isometric view thereof;

Figs. 2 and 3 are charts showing curves obtained by means of my method and apparatus and by which the grinding characteristics of an abrasive wheel may be determined and the wheel classified.

Two essential attributes of grinding are the amount of material removed from the 90 work being ground and the amount of wear of the wheel. I propose to classify wheels by utilizing these two functions, as measured under actual grinding operations. This method may be carried out by an apparatus 95 of the type illustrated in the drawing, according to which I may measure the decrease in size of the grinding wheel and a value which varies with the decrease in size of the tool or the movement of the work 100 towards the wheel. These measurements may be made either as instantaneous observations or as continuous records. To illustrate both of these methods, I have shown a recording device for indicating tool wear 105 and other characteristics associated with the grinding action and a micrometer device for measuring the wheel wear.

In accordance with my invention, I mount the grinding wheel, whose characteristics are to be determined, upon a spindle and rotate it at a standard velocity which is preferably representative of the speed at which such a grinding wheel is ordinarily rotated in actual use. I then grind thereby a tool held against the wheel under constant pressure preferably for a definite period of time 10 and I determine, in accordance with this embodiment of my invention, the decrease in size of the wheel and the forward movement of the tool. The difference between these two measurements indicates the amount of 15 the tool removed. As shown in Fig. 1, the wheel 10 may be mounted upon suitable supports 11 for positive rotation by suitable driving means. The tool 12, comprising in this instance a bar of iron, is also mounted 20 preferably on the same standard 11 in a support or carriage 13 which permits the tool to be moved longitudinally against and away from the wheel. While I may traverse the work and the wheel relative one to the 25 other, I have illustrated the tool 12 in this embodiment as being as wide as the wheel, thereby obviating the necessity for such traversing motion as might be required for a narrow tool. The carriage 13 may comprise 30 a rigid hollow member within which the tool 12 slides, the latter being fixed relative thereto in any adjusted position by means of a set screw 14. In order that the tool 12 may be moved forward as it is ground away the carriage 13 is mounted for longitudinal movement between two pairs of rollers 15 and 16, these rollers being suitably supported preferably upon the framework 11. The tool 12 35 may be held in a forward position against the wheel by means of a weight 17 having a cord 18 which passes over a pulley 19 loosely mounted on a shaft 20, this cord 18 being fastened to a pin 21 on the carriage. 40

In order to obtain measurement of the decrease in size of the grinding wheel during a classification operation, I may provide a micrometer device comprising a screw 30 mounted in the arm 31 carried by the support 11 in such a position that its lower end 45 32 may be brought into contact with the rotating wheel by the turning of the screw by means of the head 33. The head 33 is provided with a scale 34 which may be read by means of a pointer 35 projecting upwardly 50 from the arm 31, these graduations being in any suitable dimension or proportion of parts indicating a change in volume of the wheel. In operation, the screw-threaded member 30 may be turned downward until 55 60 the point 32 just touches the wheel and produces a spark. A reading for this position is then taken. Any decrease in size of the wheel may be shown by making a similar reading after a period of grinding. It is to 65 be noted that this construction enables one

to obtain an instantaneous measurement of the size of the wheel during rotation thereof.

In order to ascertain the wear on the tool, I may provide a recording mechanism which gives one a continuous portrayal of the grinding action. For this purpose, I provide an arm 40 carrying at its outer end a recording instrument such as a pencil 41 and having on its other end a ball 42 engaging a socket in an upright slidable block 43 adjustably fastened to the carriage 13. This adjustment may be effected by providing the member 43 with a groove 44 and projection 45 cooperating with a correspondingly shaped projection 46 and a dovetail slot 47 on the carriage 13, a set screw 48 being provided for locking the adjustable member 43 in any desired position. The arm 40 is pivoted on the spindle 49 located adjacent to its ball end, whereby a slight movement 85 of the carriage is magnified at the recording end of the arm. To make a record of the movement of this arm 40, I may provide any suitable recording mechanism, comprising a strip of paper 50 moved continuously by a 90 suitable mechanism over a table 51 and in contact with the recording instrument 41. As illustrated, the operating mechanism may comprise a motor 52 cooperating through a worm and gear 53 with rollers 54 which frictionally engage the paper 50 and move it at a desired rate.

In operating this device and carrying out my method, I mount the wheel 10 upon its spindle for rotation at the desired speed. 100 The tool 12 which has been selected for this operation is fastened to the carriage 13 and the adjustable block 43 is moved relative to the carriage until the recording instrument 41 marks the paper 50 at a zero line 105 55, when the tool 12 is held against the grinding face of the wheel by means of the weight 17. The paper 50, which may be suitably marked with cross section lines to indicate time intervals, is moved at a desired 110 rate corresponding with the spacings on the paper and the grinding wheel 10 is rotated at its normal rate after a measurement has been taken on the micrometer scale 34 to determine the initial size of the wheel. 115 Grinding upon the tool 12 is then started and the device allowed to record the movement of the tool as it is ground away, this record being shown in the line 56 on the paper 50. After this test has been carried on for a sufficient length of time, a second reading of the scale 34 is made and the decrease in size of the wheel noted. From the data obtained, one may determine the grinding characteristics of the wheel for the particular tool being used.

While I may conduct all the tests with one or a few tool materials, yet to take care of the different types of work, I preferably select materials for the tool which correspond 130

or have a definite relationship to the work which the wheel is intended for or best adapted to do. For example, if a given wheel is intended particularly for grinding soft materials like brass, I propose to utilize for the tool brass or some soft material which has similar grinding characteristics. It is however entirely feasible to use one tool for the whole series of wheels or to select therefor a set of metal tools carefully graduated in hardness and other physical characteristics.

The curves shown in Fig. 2 are typical of curves obtained on the paper 50. The line 55 in Fig. 1 corresponds with the X-axis and is graduated for definite intervals of time. The Y-axis, graduated either in linear measurements or according to some desirable units, indicates the sum of the tool wear and the wheel wear or a value which varies with the forward feed of the tool during grinding. If desired, one may take instantaneous measurements of the wheel wear and plot a new curve, different from the one recorded in the apparatus, to indicate the tool wear alone, or if one uses a recording instrument for determining the wheel wear one may form a third curve from the two recorded curves.

Analysis of the curve A in Fig. 2 shows that the grinding action of the wheel which produced this curve was fairly uniform at first. If this rate had remained uniform, the curve would have been a straight line as indicated by the line B. Due, however, to the abrasive particles ceasing to cut effectively, for any reason, such as dulling, glazing or loading, the curve gradually bent away from this straight line, at first at a slow rate and then, at the approximate location C, at a very rapid rate until the curve became nearly horizontal. This bend or break in the curve at C indicates the time at which the abrasive power of the wheel became so reduced as to make the wheel unfit for further service without dressing. The curve D indicates a wheel which has a much more rapid cutting ability at first but becomes unservicable much sooner than the wheel A, while the curve E indicates a wheel of slow grinding ability but which does not readily glaze. The wheels represented by these separate curves are each efficient in some particular field and it is one of the purposes of my invention to obtain a quick and accurate classification of these wheels relative to the various grinding operations. If very rapid cutting is desired even at the expense of frequent renewal of the surface of the wheel one corresponding with curve D may best be used, while for general purpose work involving grinding continuously without redressing, a wheel of the characteristics of E may be better than one of the characteristics of D.

In order to classify these wheels in accordance with their hardness of bond and the ability of the wheel to stand up under the strains of grinding, I provide further curves as shown in Fig. 3, which represent values obtained on a set of standard wheels intended for comparison with the wheels under classification. The curve M represents the tool wear or other values corresponding with those recorded by my apparatus and the curve W represents the wheel wear as determined by tests with wheels of all the different grades, the ordinates of the two curves being either of the same or of different values and the abscissas representing grades from soft to hard on any desired scale. Each standard wheel is tested by grinding a standard tool and the tool movement and the wheel wear are determined after a definite period of grinding, the data thus obtained by these separate measurements being plotted to form two separate curves having the same scale for the X-axis, the curves M and W illustrated being merely typical and not necessarily accurate in shape for any particular set of standards. With these standard curves, I may compare any other wheel which is to be classified by means of the measurements obtained in the apparatus described and so determine not only its grade but also other characteristics showing whether the wheel is more or less efficient than another wheel.

Suppose that the standard wheel and the wheel to be classified have been used for grinding the tool for T time, and the conditions of classification have been the same. As shown by the recorded characteristics of wheel A, (Fig. 2) the point K corresponding with time T has a tool wear of R, it being noted that the expression "tool wear" is used broadly to cover either the actual wear of the tool or values which vary with the wear or grinding action on the tool such as the tool movement described. A corresponding point P which has the same tool wear value R as point K is then located on the curve M in Fig. 3. A perpendicular dropped from the point P intersects the curve W at the point S and the X-axis at, we will say, grade 5. As shown by curve W a standard wheel of grade 5 gives a wheel wear of S. If now the wheel wear measurement made by means of scale 34 gives a value of X then the wheel wear of the unclassified wheel is greater than the wear of the standard wheel, and if the point is located at Y, it is less, thereby showing whether the wheel under consideration is better or poorer than the standard for a given type of grinding operation. If desired, one may utilize the wheel wear instead of the tool wear measurements for determining the grade, in which case the data obtained by means of the micrometer and scale

34 is plotted on the curve W in Fig. 3 and the grade is found to be that represented by the X-value of point S. If the point P is plotted for the wear value R of point K, then its location relative to the curve M determines whether or not the wheel is more or less efficient than the standard wheel.

It is to be noted that the hardness grade of the wheel is determined by the location on 10 one of the two standard curves of a point determined either by measuring the wheel wear or by measuring the tool wear under actual grinding conditions. Furthermore, one need not plot these curves in order to 15 obtain a classification for the wheels since it is sufficient to compare the measurements of the test with charts made up from data obtained on standard wheels, or one may make comparative tests of the new wheel and 20 another which is supposed to be substantially the same and is used as a standard. Furthermore, this invention of mine lends itself to making absolute measurements of hardness and grinding characteristics of a 25 wheel in which comparison with other standards is not necessary, the values obtained by means of my apparatus being used directly as grade or classification markings. While the term "abrasive wheel" has been 30 used throughout this specification it is obvious that the invention is applicable to classify all similar abrasive articles irrespective of their uses, provided it is feasible to abrade a wearable tool thereby.

35 In accordance with this invention I have provided a simple apparatus which may be easily constructed and manipulated and which will determine the grade and classification of a wheel in a reasonable time, and 40 I have provided moreover a method of classification which may be utilized to give the manufacturer and the wheel user more data than heretofore available for determining what wheel is best for a given type of 45 grinding work.

I claim:

1. The method of classifying a grinding 50 wheel comprising the steps of rotating the wheel at a normal grinding velocity, grinding a standard wearable tool thereby under uniform pressure and for a definite period, making successive determinations of the grinding effect of the wheel on the tool as the operation proceeds, measuring the wheel 55 wear produced in the time interval, and from the grinding characteristics thus observed

classifying the wheel by comparison with data obtained with standard wheels.

2. The method of classifying an abrasive 60 wheel comprising the steps of rotating the wheel at a grinding velocity, grinding a standard wearable tool therewith by forcing it against the wheel under constant pressure, measuring the forward movement of the tool during the grinding operation and measuring the wheel wear produced in the same 65 time interval, so that comparison of such measurements with like measurements obtained with other wheels will determine the relative grinding effects of the wheels 70 being tested upon the tool.

3. The method of classifying grinding 75 wheels comprising the steps of rotating each wheel at a normal grinding velocity, grinding a standard wearable tool thereby for a 80 definite period and under a uniform pressure, ascertaining the forward movement of the tool towards the wheel for successive time intervals, measuring the wheel wear during a given time interval, and comparing the data thus obtained for the different 85 wheels to determine their relative grinding effects upon the tool.

4. A machine for classifying an abrasive 90 wheel comprising means for supporting and rotating the wheel to be classified at a grinding velocity, a wearable tool, means to support the tool and hold it under constant pressure against the grinding wheel, a measuring device mounted on the machine having 95 a member which is manually adjustable into momentary contact with and away from the wheel to indicate the decrease in the size of the wheel during rotation thereof, and means to indicate the forward movement of the 100 tool as it is ground.

5. A machine for classifying an abrasive 105 wheel comprising means for supporting and rotating the wheel at a grinding velocity, a wearable tool, means to support the tool and hold it under constant pressure against the grinding wheel, automatic means to draw a graph representing the movement of the tool during the time of the grinding operation and a micrometer screw adjustably 110 mounted upon the machine to make an instantaneous measurement of the wheel wear during the same period.

Signed at Worcester, Massachusetts, this 28th day of February, 1919.

CHARLES E. GILLETT.
